UNITED STATES PATENT OFFICE.

ALEXANDER J. RUDOLPH, OF CHICAGO, ILLINOIS.

MACHINE FOR FORMING NECKS OF BOTTLES.

SPECIFICATION forming part of Letters Patent No. 631,329, dated August 22, 1899.

Application filed March 5, 1898. Renewed May 4, 1899. Serial No. 715,589. (No model.)

To all whom it may concern:

Be it known that I, ALEXANDER J. RUDOLPH, a citizen of the United States, and a resident of Chicago, Cook county, Illinois, have invented a new and useful Improvement 5 in Machines for Forming the Necks of Bottles, of which the following is a specification.

The object of my invention is to provide a machine which will form the necks of bottles 10 while in a soft heated state in substantially the same manner that they are now formed by the hand-tool, only more perfectly.

Heretofore the hand-tool has been almost exclusively used, because the machines for 15 this purpose are found incapable of doing the work with precision and economy. The hand-tool, which requires superior skill for the operator, consists of a central fixed piece or mandrel to form the inside of the neck and 20 two former-pieces mounted on spring-levers which are pressed together upon the neck to be formed by hand. The machines heretofore invented operate substantially on the same principle as the hand-tool. All of these 25 methods are more or less objectionable in that they do not impart a perfect parallel movement to the forming mechanism, and therefore do not uniformly distribute the glass in the neck, but make an irregular-shaped and 30 crooked neck.

My invention aims at overcoming these objections by causing the former to approach upon the neck in parallel lines with even gradual movement, pressing out the glass uniformly and forming a more perfect neck.

The economy and simplicity of my machine consist in forming the necks by a perfect parallel movement of the formers from beginning to end and having sufficient time for 40 rotating the formers over the shaped neck before hardening of the glass takes place, thereby giving additional polish to the finished article.

My invention consists of details hereinafter 45 fully described and particularly pointed out in the claims.

Figure 1 is a side elevation of my machine. Fig. 2 is a top view of a portion of the same. Fig. 3 is a sectional view on lines 3 3, Fig. 1. 50 Fig. 4 is a sectional view on lines 4 4, Fig. 1. Fig. 5 is an end view of the portion of the ma-

chine at the mandrel. Fig. 6 is a sectional view on lines 6 6, Fig. 1.

A represents the supporting-bracket; B, the pulley; C, the shaft; D, the bell-crank lever; 55 E, the sliding sleeve; F F, the links; G G, the levers attached to the links F F; H, the mandrel; I I, the formers; J J, the parallel bars, to which the formers I I are attached; K, the cleat, which supports the inner ends of J J; 60 L, the abutting block on the mandrel, against which the bottle-neck is pressed; M, the pin in the mandrel, which passes through the formers I I; N, the foot-lever, by which the pressure at the formers is applied, and O the 65 spring by which the formers are separated.

The shaft C is driven by the pulleys B and carries with it the links E F, &c., by which the formers I I are operated, the sliding sleeve E being provided with a spline e, which the 70 feather e' upon the shaft engages. The rollers d' d' upon the bell lever-crank D run in the groove d'. The links F F are attached one end to the sleeve E and the other end to the levers G G. The levers G G are bifurcated and pivoted on the bolt d at the middle crossing-point to the sleeve b upon the shaft C and are attached one end to F F and the other end to the parallel bars J J at the pivots g. The bolts j j extend from one arm 75 80 to the other of G G and slide in the ways a a in the parallel bars J J. The cleat K is secured to the shaft and rests against the inner ends of J J to support and steady them.

The formers I I are attached to the outer 85 ends of J J by the bolts i i. The mandrel H is attached to the shaft C at the joint h, so that it may be removed and replaced when damaged. The block L is attached to the mandrel and forms an abutment against which 90 the top of the neck of the bottle is pressed. The pin M is secured in this block L and passes through the formers I I, which slide in and out on it and are retained in place by it. These formers are given different contours on the inner face, according to the 95 shaped neck it is desired to form on the bottle.

The operation of my invention is as follows: The neck of the bottle to be formed is slipped onto the mandrel H while still soft (the 100 machine being in operation and the formers rotating) and the end of the neck forced up

against the block L until the neck is brought to the proper length. The foot-lever N is then pressed down gradually, bringing the formers I I up about the neck of the bottle 5 and the parts of the machine into the position shown in dotted lines, Fig. 1. The rotation of the formers in this position quickly brings the soft and cherry-red heated glass of the neck into the formers, pressing out 10 the superfluous glass and giving the desired shape to the neck.

It will be seen that by the mechanism which I have described the formers I I are made to approach one another in parallel lines instead 15 of swinging on a hinge, as has been heretofore customary in machines of this class. This gives a much more perfect forming effect, and each neck can be brought down more exactly to the same pattern with the 20 least expenditure of power and time.

It will be observed that the formers are supported, through the medium of the bars J J, solely by the levers themselves without employing a cross-head or other guideway for 25 slide-blocks. The movement of the formers is therefore a free one, unhampered by any sliding action other than that of the bolts *jj* in the ways *a a*.

What I claim, and desire to secure by Letters Patent, is—

1. A machine for forming the necks of bottles consisting of the combination of a mandrel portion adapted to be inserted within the neck of a bottle, rotating formers for finishing and forming the bottle-neck, and lever mechanism for operating such formers to and from the bottle in parallel lines, said formers being supported wholly by the lever mechanism, substantially as described.

2. A machine for forming the necks of bottles consisting of the combination of a rotating mandrel adapted to be inserted within the neck of a bottle, rotating forming mechanism laterally movably mounted upon the mandrel so as to be rotated, and levers for moving the formers to and from the bottle in parallel lines, said formers being supported wholly by the lever mechanism, substantially as described.

3. A machine for forming the necks of bottles, the combination of a rotating shaft carrying a rotating mandrel adapted to be inserted in the neck of a bottle, forming mechanism mounted upon the shaft and adapted 55 to be moved in and out to contact the bottle-neck, and lever mechanism pivotally connected to the shaft and to the formers to move the formers inwardly and outwardly in parallel lines, said formers being supported wholly 60 by the lever mechanism, substantially as described.

4. A machine for forming the necks of bottles, the combination of a shaft carrying a mandrel portion adapted to be inserted with- 65 in the neck of a bottle, forming mechanism mounted upon the shaft, lever mechanism for moving the forming mechanism inwardly

and outwardly in parallel lines, said forming mechanism being supported wholly by the lever mechanism, mechanism for preventing the longitudinal movement of the forming mechanism, and mechanism for rotating the parts, substantially as described.

5. A machine for forming the necks of bottles, the combination of a shaft carrying a mandrel portion adapted to be inserted within the neck of a bottle, forming mechanisms mounted upon the shaft and adapted to be moved inwardly and outwardly in parallel lines, mechanism for preventing longitudinal movements of the forming mechanisms, cross-levers pivotally secured together and to the forming mechanism to move the same inwardly and outwardly in parallel lines, a longitudinally-movable sleeve and link mechanism connecting the longitudinally-movable sleeve to the operating-levers of the forming mechanisms whereby the longitudinal movements of the sleeve impart parallel movements to the forming mechanism, substantially as described.

6. The herein-described machine for forming the necks of bottles, consisting of the combination of the mandrel H, the rotating formers I I, the bars J J to which said formers are attached, the bifurcated levers G G pivoted at their crossing-point, attached, one end to said bars J J, and the other end to the links F F, the sliding sleeve E, the links F F, connecting the sleeve E with the levers G G, the bell lever-crank D, which engages said sleeve E, and means for throwing said crank; all substantially as shown and described.

7. The herein-described machine for forming the necks of bottles, consisting of the combination of the mandrel H, the pin M therein, the rotating formers I I, engaged by said pin, the bars J J, to which said formers are attached, the bifurcated levers G G pivoted at their crossing-point, attached, one end to said bars J J, and the other end to the links F F, the sliding sleeve E, the links F F, connecting said sleeve E with said levers G G, the bell lever-crank D which engages said sleeve E, and means for throwing said crank; all substantially as shown and described.

8. The herein-described machine for forming the necks of bottles, consisting of the combination of the shaft C, the mandrel H, thereon, the formers I I, the pin M, upon said mandrel and engaging said formers, the bars J J which carry said formers, the levers G G hinged upon J J at *g g*, and pivoted at their crossing-points to the sleeve *b*, the bolts *jj*, upon said levers G G, which slide in the ways *a a* in said bars J J, the sliding sleeve E upon said shaft, having the spline *e'*, the links F F connecting said sleeve E with said levers G G, the feather *e* upon said shaft C upon which said spline *e'* slides, and means for throwing said sleeve E back and forth upon said shaft; all substantially as shown and described.

9. The herein-described machine for forming the necks of bottles consisting of the com-

bination of the shaft C, the mandrel H there-
on, the formers I I, the pin M upon said man-
drel and engaging said formers, the bars J J
which carry said formers, the levers G G
hinged upon J J, and pivoted at their cross-
ing-points to the sleeve b, the bolts j j upon
said levers G G which slide in the ways a a
in said bars J J, the cleat K which is attached
to said shaft C, and which engages the inner

ends of J J, the sliding sleeve E upon said shaft, the links F F, connecting said sleeve E with said levers G G, and means for throwing said sleeve E back and forth upon said shaft C; all substantially as shown and described.
